UNITED STATES PATENT OFFICE.

ABRAHAM JACKSON SYPHER, OF IRON MOUNTAIN, MISSOURI.

STEAM ROCK-DRILL.

SPECIFICATION forming part of Letters Patent No. 389,775, dated September 18, 1888.

Application filed August 6, 1887. Serial No. 246,266. (No model.)

To all whom it may concern:

Be it known that I, ABRAHAM JACKSON SYPHER, a citizen of the United States, residing at Iron Mountain, in the county of St. Francois and State of Missouri, have invented certain new and useful Improvements in Steam Rock-Drills; and I do hereby declare the following to be a full, clear, and exact description of the invention, such as will enable others skilled in the art to which it appertains to make and use the same.

My invention relates to steam rock-drills.

The object of my invention is to improve the general construction of rock-drills, especially that part that relates to the valve mechanism; and the nature of my invention consists in constructions and combinations, all as will hereinafter be set forth in the specification, and pointed out in the claims.

20 In the drawings, Figure 1 is a central vertical section on the line V, shown in Fig. 3. Fig. 2 is a front view showing section on line W, shown in Fig. 1. Fig. 3 is a central cross-section on line Y, shown in Fig. 1. Fig. 4 is a 25 top view of section of upper head on line X, shown in Fig. 1.

A represents the cylinder, having main steam-passages a a' in the walls thereof, the supplemental passage a^2 , and an opening, a^3 , closed 30 by a block, a^4 , having an arc-shaped passage, a^5 , opening into the cylinder.

A' is the upper cylinder-head; A², the lower cylinder-head; A³, the piston, having inverted inclines or shoulders a^6 ; B, the casting containing the steam-chest, the valves, and the steam passages or ports; C, the gland, and D the piston-rod and tool-holder.

40 The casting B has a cylindrical opening or valve-seat, b , for the valve B'. The upper part of this valve has a cove or cavity, b' , which serves as a steam-chest and is connected with a steam-supply pipe by means of a passage, b^2 , which extends upwardly into the casting. Leading from the steam-chest are two 45 ports, b^3 b^4 , which alternately register with the main steam-supply passages b^5 b^6 , which form a continuation of the main supply-passages a a' . The lower part is provided with coves or cavities b^7 b^8 , which alternately register with 50 the branch exhaust-passages b^9 b^{10} of the main passages b^5 b^6 and with the steam-exhaust pas-

sage B², formed below the valve and extending through the wall of the cylinder to the pipe B³. The blank spaces or segments between the passages b^5 b^6 and b^9 b^{10} serve as the 55 cut-offs for the valve. In the under side of the valve is a tappet-arm, b^{12} , secured by a pin, b^{13} . This arm projects downwardly through the exhaust-passage into a slot formed in the arc-shaped valve-driver located in the 60 arc-shaped passage in the block that fills the opening a^3 in the cylinder. This arc-shaped valve-driver is slightly longer than the passage and projects into the cylinder at a point opposite the depression in the piston and between the inverted shoulders, so that as the piston is moved upward and downward the ends of the valve-driver are alternately pushed in the passage to vibrate the valve by means of the arm secured to its under side, and thus 65 alternately cut off the supply of steam to the main and branch passages leading to and from the cylinders. By using the block a^4 and placing the tappet-arm on the valve it is obvious that the greater part of the wear will be upon 70 the block and the valve-driver, which, when they become worn, can be removed and new ones inserted without the necessity of changing the valve or any other part of the mechanism.

75 It is desirable in operating this class of devices to prevent the piston from pounding against the upper head of the cylinder. To prevent this pounding, I provide a space which, when used with the following-described means, 80 forms an air-cushion between the piston and upper head. The means referred to are an air-passage, a^6 , formed in the upper part of the body of the cylinder and opening at its lower end into the steam-passage a' and at its 85 upper end, a^{13} , into the cylinder, a puppet or check valve, a^7 , seated in an enlargement, a^8 , of the passage and its stem a^9 , extending into a recess, a^{10} , in the upper head of the cylinder, and a spiral spring, a^{12} , coiled upon the 90 stem for forcing the valve against its seat. When the upper end of the piston moves upwardly past the port or opening of passage a' , it forces the steam above it through the opening a^{13} against the valve a^7 , which is pressed 95 against its seat and prevents the steam contained between it and the head of the piston 100

from passing through the passage α' . Upon the lower end of the lower cylinder-head is the stuffing-box gland C, formed in two sections, C and C², secured together by a bolt, C³.

5. The drill is secured to the piston-rod by any of the well-known devices in use.

What I claim is—

1. In a rock-drill, the combination of a cylinder having main steam-passages provided 10 with branch passages and a rotary valve having a cove or cavity in the upper side, forming the steam-chest, alternately connecting with the branch passages and the exhaust-pipe, substantially as described.

15. 2. In a rock-drill, an arm securely attached to the rotary valve, in combination with an arc tappet, an arc tappet-block fitting into and forming part of the cylinder and having an arc-shaped hole lengthwise of the block, 20 into which the arc tappet is placed, and a piston with inverted inclines or shoulders, substantially as described.

3. In a rock-drill, the combination of a valve having a tappet-arm secured thereto, a cylinder having an arc-shaped passage, an arc-tappet valve-driver having a slot for the tappet-arm on the valve, and a piston having inverted shoulders, substantially as described.

4. In a rock-drill, the combination of a valve, 30 a cylinder having an arc-shaped passage, an arc-tappet valve-driver, an exhaust chamber or passage between the valve and cylinder, and a tappet-arm secured to the valve and projecting through the exhaust-passage in a slot or recess in the arc-tappet valve-driver, substantially as described.

In testimony whereof I affix my signature in presence of two witnesses.

ABRAHAM JACKSON SYPHIER.
